No. 729,935.

PATENTED JUNE 2, 1903

I. N. HENNESS.

PROPELLING DEVICE FOR ICE VEHICLES.

APPLICATION FILED JULY 24, 1902.

NO MODEL.

UNITED STATES PATENT OFFICE.

ISAAC N. HENNESS, OF ILWACO, WASHINGTON.

PROPELLED DEVICE FOR ICE-VEHICLES.

SPECIFICATION forming part of Letters Patent No. 729,935, dated June 2, 1903.

Application filed July 24, 1902. Serial No. 116,833. (No model.)

To all whom it may concern:

Be it known that I, ISAAC N. HENNESS, a citizen of the United States, residing at Ilwaco, in the county of Pacific and State of Washington, have invented certain new and useful Improvements in Propelling Devices for Ice-Vehicles, of which the following is a specification, reference being had therein to the accompanying drawings.

10 This invention relates to vehicle-propellers, and specifically to an improvement in the ice-vehicle shown and described in my application, Serial No. 96,315, filed March 1, 1902; and the object of the invention is to render 15 the device more efficient in operation.

The invention consists in a plurality of two-part longitudinal push-bars provided with track-engaging shoes at their rear ends, combined with a horizontal and transversely-arranged driving-shaft which is rotated by a connection with an engine; also, in the novel means for providing for vertical adjustment of the forward ends of said push-bars and in the novel means of conveying the power from the 25 driving-shaft to the push-bars, as will be hereinafter set forth.

In the accompanying drawings, Figure 1 is a plan view of the rear end of a vehicle with my improved propelling apparatus applied 30 thereto. Fig. 2 is a vertical longitudinal section taken on line $x-x$ of Fig. 1.

In the drawings the letter a indicates the vehicle-body, preferably made water-tight and mounted on runners b , which project 35 rearwardly therebeyond to provide an extended footing and means to support a propeller guide-frame c . Positioned within the body and preferably in proximity to the back end thereof is a transversely-arranged multiple-crank shaft d , journaled in suitable bearings e . A sprocket-wheel f is fixedly 40 mounted upon said shaft, by which the shaft is driven from a suitable motor (not shown) through the medium of a link belt f' .

45 Push-bars comprised of parts g and g' , respectively, are connected at the forward ends by means of sleeves h , formed thereon, to a horizontal shaft i , terminating at its opposite ends in blocks i' , mounted and movable vertically in adjustment-frames j by means of

take-up or set screws j' . The rear ends of the various push-bars are secured by pivots k to lugs k' of shoes l , having downwardly-projecting calks l' , whereby penetrating engagement may be had with the track-surface. 55

m indicates rods connecting the crank-pins of shaft d with the contiguous ends of the push-bars, whereby the several push-bars are alternately deflected and relatively flattened out, and consequently thrust backwardly and 60 redraw the propelling ends thereof. The office of the vertical adjustment at the forward ends of the push-bars is to regulate the length of stroke of said bars and regulate the speed and power to suit condition of track or weight 65 of sled and its cargo.

The relative sizes of the various cranks, bars, and connecting-rods should be of suitable proportions, as determined in practice; but good results are obtainable by constructing and arranging the same in the proportions shown in the drawings. 70

Having described my invention, what I claim as new, and desire to secure by Letters Patent, is—

1. The herein-described propelling means for ice-vehicles comprising, in combination, the crank-shaft d , push-bars g g' vertically-adjustable shaft i , frame j , set-screws j' , shoes l and connecting-rods m . 75 80

2. The combination with the vehicle-body, the crank-shaft journaled therein, and means for actuating the said crank-shaft, of rods connected to the cranks of the said shaft, a shaft adjustably mounted in front of the said 85 crank-shaft, means for adjusting the said last-named shaft, and push-bars consisting of two members each having one of their ends pivotally connected to the said rods, the foremost of said members having their other ends 90 sleeved on the said last-named shaft, and shoes secured to the free ends of the other members of the said push-bars, substantially as and for the purpose specified.

In testimony whereof I affix my signature 95 in presence of two witnesses.

ISAAC N. HENNESS.
